(57) **CLAIM**

The ornamental design for a vehicle rooftop, as shown and described.

DESCRIPTION

FIG. 1 is a top plan view of a vehicle rooftop showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a rear perspective view thereof; and,

FIG. 8 is a right-side perspective view thereof.

The broken line showing of fasteners and holes is included for the purpose of illustrating environmental structure and forms no part of the claimed design.
